CLAIM

The ornamental design for a clipboard, as shown and described.

DESCRIPTION

FIG. 1 is a front, bottom and right side perspective view showing my new design for a clipboard.

FIG. 2 is a front view.

FIG. 3 is a back view.

FIG. 4 is a right side view.

FIG. 5 is a left side view.

FIG. 6 is a top view; and,

FIG. 7 is a bottom view.

The broken lines showing of parts of the clipboard and a writing utensil are included for the purpose of illustrating environment and form no part of the claimed design.
